UNITED STATES PATENT OFFICE.

THOMAS H. BULLOCK, OF CLEVELAND, OHIO.

POR TABLE FORGE.

SPECIFICATION forming part of Letters Patent No. 297,494, dated April 22, 1884.

Application filed June 23, 1883. (No model.)

To all whom it may concern:

Be it known that I, THOMAS H. BULLOCK, of Cleveland, in the county of Cuyahoga and State of Ohio, have invented certain new and useful Improvements in Portable Forges; and I do hereby declare the following to be a full, clear, and exact description of the invention, such as will enable others skilled in the art to which it pertains to make and use the same.

10 My invention relates to improvements in portable forges; and it consists of certain features of construction and in the combination of parts hereinafter described; and pointed out in the claims.

15 In the drawings, Figure 1 is a vertical sectional view of a portable forge with my improvements attached. Fig. 2 is a cross-section on the line of x x , Fig. 1, showing a top view of the bellows.

20 A represents the tray or pan of a portable forge supported by the legs a , that also support the bellows B, consisting of the top part, b , and the lower part, b' , and divided by the partition b^2 . The bottom of the bellows and 25 the partition b^2 are each provided with a clap-valve, c , preferably of the kind known as "Smith's Flexible Valve," opening upward. C is a ring, preferably of metal, and concentric with the top of the bellows, so as to balance the same. This ring may be of any desired weight, according to the pressure of the blast required.

25 D is an air-tube, extending from the inside of the top part of the bellows to the tuyere E, and acts also as a guide for the bellows, the latter being provided with the thimble d , embracing the tube and sliding thereon.

30 F is a lever, connected by a wire to the lower part of the bellows, as shown, and operated in 40 the usual manner.

The bellows operates in the usual manner; except the top part does not tilt, but rises perpendicularly, and is guided by means of the thimble d , sliding on the tube D, the ring of weight C in the meantime balancing the top 45 part of the bellows, so that there is little friction between the parts D and d .

In Fig. 1 is shown a modification, in which the tuyere is at one side of the fire-pan, that necessitates an elbow in the tube D. Usually 50 these forges are made with the tuyere in the center of the fire-pan, so that the tube D passes in at the bottom of the tuyere without any crook or elbow, making a shorter passage-way 55 heretofore in use.

What I claim is—

1. The combination, with a tray and bellows, of an intermediate connecting-pipe rigidly secured at one end to the tray or tuyere, 60 and adapted to form a guide for the bellows, substantially as set forth.
2. The combination, with a tray provided with a tuyere and a bellows, the latter being provided with a weight, C, arranged concentrically with the bellows, of an intermediate connecting-pipe, the upper end of which is rigidly secured to the tuyere, while the lower portion thereof forms a guide for the bellows, 65 substantially as set forth.

In testimony whereof I sign this specification, in the presence of two witnesses, this 16th day of June, 1883.

THOMAS H. BULLOCK.
